UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A PHOTOGRAPHIC CARD-MOUNT.

SPECIFICATION forming part of Design No. 31,074, dated June 27, 1899.

Application filed June 3, 1899. Serial No. 719,812. Term of patent 7 years.

To all whom it may concern:

Be it known that I, JOHN P. ODGERS, a citizen of the United States, residing in Philadelphia, Pennsylvania, have invented a certain new and original Design for a Photographic Card-Mount, of which the following is a specification.

My design is fully shown in the accompanying drawings, in which—

Figure 1 is a face view, on an enlarged scale, of a card-mount embodying the design; and Fig. 2 is a transverse section of the same.

The design comprises a central impressed surface of round or rounded outline for receiving the picture, this surface being surrounded by a band or border composed of fine radiating ribs disposed closely side by side. This band or border is likewise impressed on

the card and is bounded on the inner side by a narrow annular rib.

In the drawings, 1 represents the depressed central surface for receiving the picture, 2 the ribbed band or border surrounding the same, and 3 the internal annular rib.

Having thus described my invention, I claim—

The design for a card-mount, substantially as described and as shown in the accompanying drawings.

In testimony whereof I have signed my name to this specification in the presence of two subscribing witnesses.

JOHN P. ODGERS.

Witnesses:

H. F. REARDON,
F. E. BECHTOLD.
